UNITED STATES PATENT OFFICE.

WILLIAM GOLDEN, OF PORT HURON, MICHIGAN.

SAW-FITTING TOOL.

SPECIFICATION forming part of Letters Patent No. 311,481, dated February 3, 1885.

Application filed May 31, 1884. (No model.)

To all whom it may concern:

Be it known that I, WILLIAM GOLDEN, a citizen of the United States, residing at Port Huron, in the county of St. Clair and State of Michigan, have invented a new and useful Saw-Fitting Tool, of which the following is a specification, reference being had to the accompanying drawings.

This invention has relation to a saw-fitting tool, combining in one tool all that is necessary to fit a saw for use—viz., a raker-gage, a jointer, a set and tooth gage, a hammer for swaging rakers or drag-teeth, and a swage for hitting on the ends of the set—as will be hereinafter fully described, and particularly pointed out in the claim.

Figure 1 is a view in perspective of my improved combination-tool, and Fig. 2 is a side elevation of the tool with the file in position for jointing the saw.

Referring by letter to the accompanying drawings, A designates the body of the combination-tool.

B designates the raker-gage, consisting of the flanged shoulders C C, between which is the depression D, having the laterally-projecting slotted flange E. The rakers or drag-teeth project up through the vertical slot E in the flange E, and are filed off even to gage the rakers. On the opposite side from the flange E is a curved lateral flange, F, and at

each end of this curved lateral flange is a laterally-projecting pin, G. The central portion of the body A is open, and is surrounded by a curved portion, H, and an oppositely-curved flanged portion, I, which form the bearings for a compressing-screw, K, which bears the file against the pins G to form the saw-jointer.

M designates the set-groove for setting large saw-teeth, and N the groove for setting small saw-teeth, and O is the set-gage, consisting of the threaded arm P and the set screw P'.

Q designates the hammer for swaging the rakers or drag-teeth of a saw, and R designates the swager for hitting on the end of the set. The portion between the shoulders of the raker-gage will be of case-hardened steel.

Having thus fully described my invention, what I claim as new, and desire to secure by Letters Patent of the United States, is—

The herein-described combination-tool for fitting saws, comprising a raker-gage, a jointer, a hammer for swaging rakers, a saw-set and tooth-gage, and a swager for hitting on the end of the set, substantially as specified.

In testimony that I claim the foregoing as my own I have hereto affixed my signature in presence of two witnesses.

WILLIAM GOLDEN.
